UNITED STATES PATENT OFFICE.

WILLIAM BOND TAYLOR, OF CARBONEAR, NEWFOUNDLAND, ASSIGNOR OF ONE-FOURTH TO FRANK P. PIKE AND ONE-FOURTH TO ALBERT E. PENNEY.

TWISTING DEVICE.

Application filed May 13, 1925. Serial No. 29,952.

To all whom it may concern:

Be it known that I, WILLIAM BOND TAYLOR, a subject of the King of Great Britain, and a resident of Carbonear, Newfoundland, have invented certain new and useful Improvements in Twisting Devices, of which the following is a specification.

This invention relates to twisting devices and is herein illustrated as embodied in a device especially adapted to be used in tightening the wires used in binding concrete forms which may eventually serve to reinforce the molded concrete structure.

Such devices must be strong, of simple construction so that no parts are likely to be clogged, and must be adapted to reach into and operate in places difficult of access.

According to the present invention all these advantages are obtained in a device cheap to construct and easy to use.

In the accompanying drawings:

Figure 1 is an end view of one form of the device, certain parts being broken away to better show the structure.

Figure 2 is a side view with other parts broken away, and

Figure 3 is a sectional view at the line 3-3 of Figure 2.

In using the device to twist two wires together the handles 1, 2 are operated scissor-fashion, one after the other, to cause their respective pawls 3, 4 to alternately engage the respective ratchet wheels 5, 6 and rotate the hub 7 to bring the wire receiving openings or slots 8, 9 clear of the extension collars 10, 11.

With the openings 8, 9 in this position they can respectively engage the two wires 12, 13, and the hub 7 can be seated upon the wires. Either of the handles 1 or 2 may then be operated to cause its pawl 3 or 4 to drive its ratchet wheel 5 or 6 to turn the hub 7, thus starting the twisting of the wires because they are held in their respective slots 8 and 9. The twisting of the wires to any desired extent is completed by alternately operating the handles 1 and 2 or reciprocating either of them to turn the hub 7 and with it the wires.

It will be observed that the device shown is of extremely simple construction. The two ratchet wheels 5 and 6 are preferably integral with the ends of the hub 7, and form a groove 15 between them. Each handle 1 and 2 has an ear 14 projecting into

the groove 15, so as to bear against the face of the hub, with one side of the ear lying against the flat inner face of the corresponding ratchet wheel, and the other side of the ear lying adjacent the side of the ear 14 of the other handle. Each handle 1 and 2 is also provided with a second ear 19 lying against the outer face of the corresponding ratchet wheel 5 or 6. Each ear 19 not only lies against the outer face of the corresponding ratchet wheel 5 or 6, but also carries the extension collar 10 or 11 lying in an annular groove 21 in the outer face of the corresponding ratchet wheel. In the present disclosure, the collars 10 or 11 are shown as secured to their respective ears 19 by screws 22 passing through the ears and threaded into their collars.

Each collar 10 or 11 covers the major part of the circumference of its groove 21, thus forming a wide journal for its handle on the hub, but leaving openings in said collars sufficiently long to leave both wire receiving slots 8 and 9 open when the hub is in proper position, so that both the slots may be slipped at the same time over the wires to be twisted or off the twisted wires. In the construction shown, the ends 24 and 25 of the collars 10 and 11 are beveled off so that the bevels lie nearly along the line of the adjacent edges of the slots, when the slots are open, with the result that a minimum of movement of either handle closes one or both slots and locks in place the wires to be twisted.

The pawls 3 and 4 are simply but strongly formed and mounted, in the construction illustrated. Each includes a heavy round stem 27 sliding in a round hole, drilled longitudinally into its supporting handle 1 or 2 between the ears 14 and 19; and said pawl is pressed outwardly by a coiled spring 29 so that the pawl tooth is constantly pressed against its ratchet wheel 5 or 6. The pawl teeth preferably extend across the entire width and depth of the ratchet wheel teeth, and are formed integral with the bodies of the pawls which fit closely, though sliding freely, between the ears 14 and 19 of each handle 1 and 2. In its operating position, the face of each pawl fits snugly against most of the face of the adjacent teeth of the ratchet wheel, thus supporting the pawl firmly even when it bridges the slots 8 and 9. It has been found satisfactory to have the

slots 8 and 9 spaced about three-quarters of an inch on centers at their bottom and about one-half inch at the periphery of the ratchet wheels. Twenty-four teeth in each ratchet wheel has been found satisfactory in an iron device for tightening wires in concrete molds.

Having thus described one embodiment of the invention what is claimed is:

- 10 1. In a twisting device, a hub having a pair of slots to receive wires to be twisted together, said hub also being provided on each end with a groove, a pair of handles, a collar having an opening therein and secured to each handle and running in one of the grooves in the hub to form a journal for its handle, a ratchet wheel for each handle on said hub, and a pawl carried by each handle and cooperating with one of said ratchet wheels.
- 15 2. In a twisting device, a hub having a pair of slots to receive wires to be twisted together and having an annular groove in each end, a pair of handles, a collar for each handle having an opening and running in one of the grooves in the hub to form a journal for its handle, a ratchet wheel for each handle on the hub operated by its handle, a pawl for each handle for driving its

ratchet wheel, and an ear for each handle riding beside its ratchet wheel.

3. In a twisting device, a hub including a pair of slots to receive wires to be twisted together, a pair of spaced ratchet wheels on said hub and having a groove between them, 35 said hub also having a pair of journal grooves, a pair of handles turning on the hub, a pawl carried by each handle and co-operating with one of the ratchet wheels, an annular collar for each handle having an 40 opening and running in one of the journal grooves, and an ear carried by each handle engaging in the first groove

4. In a twisting device, a hub including a pair of slots to receive wires to be twisted 45 together, a pair of spaced ratchet wheels on the periphery of the hub and having a groove between them, said hub also having journal grooves in its ends, a pair of handles turning on the hub and having pawls to engage 50 the ratchets, a collar for each handle having an opening and riding in one of the journal grooves, and an ear for each handle riding in the first groove.

In testimony whereof, I have affixed my 55 signature to this specification.

WILLIAM BOND TAYLOR.
